Daniel J. Crowley, Grosse Pointe, Mich.

Application March 21, 1938, Serial No. 197,280

6 Claims. (Cl. 250—14)

This invention relates generally to household equipment and refers more particularly to an article of furniture embodying radio receiving apparatus.

One of the principal objects of this invention consists in the ingenious manner in which the instrumentalities of a radio receiving set are distributed in the various parts of an article of furniture and also in the novel manner in which these instrumentalities are supported on the article of furniture.

Another object of the present invention consists in the provision of a construction of the character set forth in the preceding paragraph wherein the instrumentalities of the radio receiving set are not only compactly arranged in the several parts of the article of furniture in a manner such that they are substantially concealed from view but, in addition, are secured to the various parts of the article of furniture in a manner to permit the same to be readily installed in and removed from the article.

Still another advantageous feature of this invention resides in the provision of an article of furniture having a base section adapted to house certain of the instrumentalities of the radio receiving set and having a top section supported by the base section and adapted to contain additional parts of the radio receiving set. In accordance with the present invention, the power supply unit of the radio receiving set is housed in the base, while the loud speaker and chassis, including the remaining parts of the selected radio circuit, are compactly arranged in the top section of the article of furniture.

It is a further object of the present invention to construct the top unit in a manner to not only advantageously house the parts aforesaid of the radio receiving set, but to also form an effective baffle for the loud speaker unit.

A still further feature of the present invention consists in arranging the tuning unit for the radio receiving set in a position where it not only improves the artistic appearance of the article of furniture but, in addition, where it may be conveniently manipulated by the operator.

Still another object of the present invention resides in the novel construction of the tuning unit which not only provides for obtaining the artistic appearance set forth in the preceding paragraph but, in addition, renders it possible to compactly arrange the controls so that the same occupy the minimum space.

In addition to the foregoing, the present invention contemplates a construction wherein the

top section and associated instrumentalities of the radio receiving set may be readily removed from the base section without detaching any of the instrumentalities of the radio receiving set from their respective supporting sections.

The foregoing, as well as other objects, will be made more apparent as this description proceeds, especially when considered in connection with the accompanying drawings, wherein:

10 Figure 1 is a perspective view of an article of furniture having a radio receiving set associated therewith;

15 Figure 2 is a vertical sectional view through the article of furniture indicated in Figure 1 and illustrating diagrammatically various instrumentalities of the radio receiving set in their respective positions;

20 Figure 3 is a sectional view taken substantially on the plane indicated by the line 3—3 of Figure 2;

25 Figure 4 is a sectional view taken substantially on the plane indicated by the line 4—4 of Figure 2;

Figure 5 is a sectional view taken on the line 5—5 of Figure 2;

Figure 6 is a vertical sectional view of another embodiment of this invention;

Figure 7 is a cross sectional view taken on the line 7—7 of Figure 6; and

30 Figure 8 is a fragmentary sectional view illustrating a further modified form of construction.

For the purpose of illustrating the present invention, I have selected an article of furniture which may be used as a smoking stand, although 35 it will be understood as this description proceeds that the present invention is applicable to various other types of articles of furniture. In accordance with the present invention, the various instrumentalities of a complete receiving circuit, including the loud speaker assembly, are distributed in various parts of the article of furniture in a manner to not only provide radio reception comparable to conventional receiving sets, but to also impart an artistic appearance to the article of furniture. This has been accomplished, in the present instance, without interfering with the intended purpose of the article of furniture and without obscuring the controls associated with the tuning unit for the radio receiving circuit. In the case of a smoking stand, the controls are prominently located at the center of the supporting surface of the stand in a position where it may be conveniently manipulated by the operator. Attention

50 may also be called to the fact at this time that

while the various instrumentalities of the radio receiver are compactly arranged and concealed in the several parts of the article of furniture, nevertheless, the construction is such as to permit these instrumentalities to be readily assembled with the article of furniture and at the same time affords relatively easy servicing of the radio circuit when required.

In detail, I have shown in Figures 1 and 2 an article of furniture in the form of a smoking stand 10 having a base section 11 and a top section 12 supported from the base section by means of a pedestal 13. In the specific embodiment of the invention selected herein for the purpose of illustration, the base section 11 forms a support for the power supply unit 14 of the radio receiving circuit, while the top section 12 supports the speaker unit 15 and the chassis unit 16 which includes all of the various parts of the selected radio receiving circuit other than those previously mentioned. Each of the required instrumentalities of the radio receiving circuit employed in the present invention is of conventional manufacture and forms no part of this invention. Accordingly, these instrumentalities and the particular type of circuit are not shown in detail herein. It will suffice to point out that the parts of the circuit in the base 11 are electrically connected to the parts of the circuit in the top section 12 by means of suitable electrical conductors which extend through the pedestal 13.

The top section 12 comprises a hub 17 and an annular rim 18 connected to the hub through the medium of a conical disc section 19. The hub 17 is threaded upon the upper end of the tube 20 which forms the pedestal 13 and the lower end of this tube is secured to the base section 11 in a manner to be presently described.

A table top 21 is seated upon the upper edge of the rim 18 and is provided with a central opening 22 therethrough of sufficient diameter to receive the tuning unit 23 of the radio receiving apparatus. The marginal edges of the table top 21 are clamped against the upper edge of the rim 18 by means of a spider 24 having a hub 25 extending into the hub 17 of the top section 12 and having outwardly projecting spokes 26 extending substantially parallel with the inner surface of the conical section 19 of the top section. The outer ends of the spokes terminate in upwardly projecting extensions 27 secured to the underside of the table top 21 by means of the fastener elements 28. The lower end wall of the hub 25 is provided with a nut 29 threaded for engagement with the upper end of a drawbolt 30 which extends axially through the tube 20 and is provided with a head 31 cooperating with the spider 32 in the base section 11 to effectively clamp the spider 24 together with the table top 21 in assembled relation with the top section 12.

The speaker unit 15 is of conventional design and the cone 34 is secured to the spokes 26 of the spider with the hub portion 35 thereof extending into the hub 25 of the spider. The angle of inclination of the cone conforms to the angle of taper of the conical connecting section 19 of the top section 12, and the periphery of the cone may be secured to the spokes 26 of the spider 24 by means of the fastener elements 36. The arrangement is such that the conical connecting portion 19 of the top section 12 forms a baffle for the speaker and, in the present instance, the conical portion 19 is apertured, as at 37, to provide

the desired transfer of tone from the speaker unit.

The spider 32 in the base section 11 is enclosed by a cover 38 and is secured to the cover by means of the fastener elements 40 which also function to clamp a hub 39 to the top of the cover 38. The central portion of the hub is apertured to provide for extending the electrical conductors therethrough and also to permit the passage of the drawbolt 30 therethrough. The outer extremities of the spokes 40' of the spider are secured to a base plate 41 through the medium of spacers 42, and this base plate is capable of being detached from the spider by removing the screws 43.

As stated above, the power supply unit 14 is housed in the base section 11 and, in the present instance, this unit comprises a power transformer 44, a speaker transformer 45, a rectifier tube 46, and an audio tube 47. These elements are each supported from the spokes 40' of the spider by means of brackets 48 in a manner to be exposed when the plate 41 is removed from the spider. In this connection, it will be noted that the head 31 of the drawbolt 30 is also exposed when the plate 41 is removed and may be readily manipulated, when desired. The lower end of the tube 20 is removably secured to the cover 38 and spider 32 by means of a coupling 49 threaded upon the lower end of the tube and having a radially outwardly extending flange 50 secured to both the cover 38 and spider 32 by means of the fastener elements 40. The coupling 49 is concealed by a suitable cover 51 sleeved on the tube 20 and having the lower end abutting the top of the cover 38 radially outwardly beyond the flange 50 on the coupling 49. The cover 51 is detachably secured in place by means of a suitable ring 52 threaded on the lower end of the tube 20.

The chassis assembly 16 is supported in the top section 12 above the speaker unit 15 and is removably secured to the underside of the table top 21 by means of the fastener elements 28, previously referred to as securing the spider 24 to the table top 21. In the present instance, the tuning unit 23 is carried by the chassis unit 16 and may be removed with the latter as an assembly. The chassis assembly 16 with the tuning unit 23 may be removed from the top section 12 by merely detaching the base plate 41 from the spider 32 and removing the drawbolt 30. After this is accomplished, the table top 21 may be lifted from the top section 12 of the smoking stand and since the spider 24, chassis unit 16, and speaker 15 are secured either directly or indirectly to the table top 21, it follows that these elements are removable as a unit with the latter. The spider 24, chassis 16, and speaker 15 may then be detached from the underside of the table top 21 by removing the fastener elements 28.

As stated above, the various instrumentalities of the power supply unit in the base section 11 may be exposed for service or other purposes by removing the base plate 41. These instrumentalities, of course, may be detached as a unit from the base by merely removing the fastener elements 40. This permits removing the spider 32 and associated instrumentalities of the power supply unit 14 as an assembly from the stand.

It follows from the above that the various instrumentalities of the power supply unit 14 may be attached to the spider 32 and assembled in the base section 11 of the stand as a unit. It will also be noted from the above that the chassis assembly 16 and speaker unit 15 form a sub-as-

sembly with the table top 21 and may be installed as a unit with the latter.

Referring now more in detail to the tuning unit 23, it will be noted that the same is supported above the table top 21 centrally of the latter in a position to be conveniently manipulated by the operator and comprises two controls 60 and 61. The control 61 is operatively connected to a combined rheostat and "Off" and "On" switch 63 supported on the chassis assembly in a manner to be presently described. In accordance with conventional practice, the rheostat controls the volume of the radio receiver and the switch selectively connects the receiver to and disconnects the same from a source of power supply. The control 60 is operatively connected to the variable condensers 64 arranged on the chassis assembly and connected in the circuit to provide for varying the capacitance of the circuit.

Upon reference to Figure 2, it will be noted that each of the variable condensers 64 is provided with a stator 66 having vertically spaced plates 67 and is also provided with a rotor 68 having plates 69 respectively movable between adjacent stator plates by means of a rotatable shaft 70. A pinion 71 is secured to the upper end of each rotor shaft 70 and the condensers are so arranged with respect to each other that the pinions 71 mesh with a common centrally disposed driving gear 72. The pinions 71 and driving gear 72 are positioned above the top wall 73 of the chassis casing 74 and the driving gear 72 is rotatably supported on the upper end of a tubular inverted cup-shaped housing 75 extending axially through the casing 74.

The gear 72 is rotated at a reduced speed from the control disc 60 and this is accomplished in the following manner. The control disc 60 is in the form of a ring having teeth on the inner annular surface thereof meshing with a pinion 76 mounted on a carrier 77 and, in turn, meshing with a gear 78 fixed to a tube 79 extending axially upwardly from the top of the inverted cup-shaped element 75. The lower end of the supporting tube 79 has a pressed fit in an opening formed in the top of the element 75 and, as a consequence, is held from rotation. As a result, rotation of the control disc 60 effects a rotation of the carrier disc 77 at a reduced speed.

The carrier disc 77 is operatively connected to the driving gear 72 by a tube 80 concentrically arranged with respect to the tube 79 and having circumferentially spaced projections extending axially of the tube 80 from opposite ends thereof into slots 81 and 82 formed respectively in the carrier disc 77 and hub 83 of the driving gear 72. The construction is such that rotation of the control disc 60 effects a rotation of the driving gear 72 and rotors of the several condensers at a reduced speed.

Provision is made in the driving connection between the control 60 and gear 72 to take up any back lash that may exist in the mechanism. In the present instance, the pinion 76 is rotatably carried by one end of a link 85 having the opposite end pivoted to the carrier disc 77. The pinion 76 is, in effect, clamped between the teeth on the control disc 60 and the fixed gear 78 by normally urging the control disc 60 in a direction toward the pinion 76. This is accomplished by providing a spring 86 mounted on a stud 86' having the inner end extending through an opening in a lug 85' projecting upwardly from the carrier disc and secured to the tube 80. The inner end of the

spring abuts the lug 85' and the outer end of the spring engages a nut 84 secured to the outer end of the stud. As shown in Figure 2, the carrier disc 77 has a running fit with the tube 79 and is held from lateral displacement by the latter with the result that the spring 86 acts on the tube 80 tending to move the same laterally relative to the tube 79. The tube 80 rotates as a unit with the carrier disc and the slots 81 and 82 for receiving the driving projections at opposite ends of the tube 80 are elongated to provide for lateral displacement of the tube 80 relative to the carrier disc. The central opening 87 through the hub portion 83 of the control disc 60 has a running fit with the tube 80 and, as a result, moves laterally relative to the carrier disc as a unit with the tube 80. Remembering that the spring 86 is located diametrically opposite the pinion 76, it follows that the control disc 60 is yieldably urged toward the pinion 76 to clamp the latter between the teeth on the control disc and the fixed gear 78.

In accordance with general practice, provision is made herein for indicating the various broadcasting stations according to their respective frequencies and the indicia required for this purpose is applied to a band 89 fixed to the control disc 60. The band extends downwardly from the control disc and is visible through a window or opening 90 in a casing 91. The casing 91 forms an extension of the top wall of the chassis casing and projects upwardly from the latter through the opening 22 in the table top 21. It will, of course, be understood that the window 90 is formed in the portion of the casing 91 projecting above the table top and that the location of the band 89 is determined to be clearly visible through the window.

The control 61 is located above the control 60 and is fixed on a shaft 92 extending axially of the casing 91. The lower end of the shaft 92 is operatively connected to the combined rheostat and switch 63 in the orthodox manner so that initial rotation of the control 61 in one direction operates the switch to close the circuit to the receiving apparatus, and continued rotation operates the rheostat to increase the volume. Of course, rotation of the control 61 in the opposite direction decreases the volume and opens the circuit aforesaid.

Referring now to the embodiment of the invention illustrated in Figures 6 and 7, it will be noted that this construction differs essentially from the above described form in that the same is equipped with two speaker units, one in the base section 94 and the other in the top section 95. One speaker is preferably adjusted to deliver the higher notes and the other the lower notes, with the result that the ultimate reception is substantially free from distortion. In detail, the base section 94 is provided with a cover 96 having an annular rim 97 and a centrally disposed upwardly projecting hub 98 integrally connected to the rim by a conical disc portion 99. A dynamic speaker unit 100 of conventional design is located in the cover 96 with the hub portion 101 of the speaker extending into the hub 98 of the cover and with the cone extending substantially parallel to the lower surface of the conical connecting portion 99 of the cover. In the present instance, the periphery of the cone is removably attached to the cover 96 by means of brackets 102 and the cover is apertured, as at 103, to provide the desired tone transfer.

A power supply unit 14' identical to the one

previously set forth in connection with the first described form of the invention is mounted on a base plate 104 which, in turn, is detachably secured to the conical portion 99 of the cover 96 by screws 105. As a result, the power supply unit 14' may be detached as an assembly with the base plate 104 by merely removing the screws 105.

The upper end of the hub portion 98 of the cover 96 is threaded for attachment to the lower end of the pedestal 106 having the upper end threadedly connected to a hub 107 depending from the top section 95. The top section 95 is substantially cup-shaped in cross section and is closed at the upper end by a table top 107 seated on the upper edge of the annular wall 108 of the cup-shaped top section. The top section 95 houses a chassis unit 109 having a control unit 110 extending upwardly through a central opening 111 in the table top 107 and having a pair of controls 60' and 61' accessible for convenient manipulation by the operator. The chassis unit 109 and associated control unit 110 are identical in construction to the chassis 16 and control unit 23 described in detail in the above embodiment of this invention.

The second speaker unit 112 is housed by the top section 95 and is supported below the chassis 109 by a spider 113. The spider 113 has a hub 114 of sufficient dimension to receive the hub 115 of the speaker and is also provided with radially outwardly extending spokes 116 having the outer ends removably secured to the chassis 109 by screws 117. The spokes 116 are shaped to form seats for the cone 118 of the speaker unit and the periphery of the cone is secured to the spokes by screws 119. Either or both the annular side wall 108 or the top wall 107 of the top section 95 are apertured to provide tone transfer from the speaker. The two speakers are, of course, electrically connected in the receiving circuit in accordance with orthodox practice so as to operate in conjunction with one another.

The top wall 107 is clamped against the upper edge of the annular side wall 108 by a bolt 125 extending axially through the pedestal with the upper end threadedly connected to the lower end of the hub 114 on the speaker spider 113 and having a head 126 at the lower end abutting the bottom surface of the hub 98 on the cover 96. The bolt is accessible upon removing both the power supply unit 14' and the speaker 100 from the base. It follows, of course, that removal of the bolt 125 permits the table top 107, chassis 109, and speaker 112 to be lifted from the top section 95 as an assembly. This sub-assembly may be readily disassembled after it has been removed from the pedestal.

The embodiment of the invention shown in Figure 8 may be incorporated in either or both of the foregoing modifications, if desired, and consists in providing a detachable electrical connection between the radio receiving instrumentalities in the top section of the stand and the parts in the base of the latter. In detail, a disc 120 is suitably secured in the upper end of the pedestal and is formed with the required number of sockets 121 therein which are electrically connected to those instrumentalities in the base section it is desired to electrically connect to the parts in the top section. A cooperating disc 122 is secured to the hub 25 by welding or the like and this disc is provided with plugs 123 corresponding in number to the sockets 121. The plugs are respectively electrically connected

to the parts of the circuit in the top section it is essential to connect to the instrumentalities in the base and are adapted to have a sliding fit with the sockets 121. As a result, the top section may be readily removed from the pedestal without detaching the electrical conductors from the various instrumentalities of the radio circuit and this is desirable in that it permits permanently securing the ends of the conductors to the several parts of the radio set.

What I claim as my invention is:

1. In a combined article of furniture and radio receiving set, a stand having a base section provided with top, bottom, and side walls defining an enclosed space, a pedestal extending upwardly from the base, a top section supported on the top of the pedestal and having a top wall, a radio receiving set having a chassis unit suspended from the top wall of the top section and comprising a plurality of parts of a radio circuit, means securing the chassis unit to the top wall of the top section, additional parts of the radio circuit housed in the base section and electrically connected to parts in the chassis unit through the pedestal, tuning control elements located above the top wall of the top section and operatively connected to certain of the parts of the circuit in said chassis through an opening in the top wall of said top section, a loud speaker unit positioned between the chassis unit and upper end of the pedestal, and means for securing the loud speaker unit to the top wall of the top section.

2. In a combined article of furniture and radio receiving set, a stand having a base section and having a top section supported above the base section by a pedestal, said top section having top, bottom and side walls defining an enclosed space, a radio receiving set having a chassis unit comprising a number of parts of the radio circuit and housed in the top section, additional parts of the radio receiving circuit housed in the base and electrically connected to certain parts of the chassis unit through the pedestal, a loud speaker unit comprising a cone-shaped diaphragm secured in the top section beneath the chassis unit with the cone facing upwardly, and tuning control elements supported above the top wall of the top section one above the other and respectively operatively connected to different parts of the radio receiving circuit.

3. In a combined article of furniture and radio receiving set, a stand provided with a hollow base section having a removable bottom wall, a hollow top section supported above the base section by a pedestal and having a removable top wall, means accessible for manipulation upon removing the bottom wall of the base section and effective to secure the top wall of the top section in place, a radio receiving set having certain parts secured to the underside of the top wall of the top section within the latter and having other parts secured to the bottom wall of the base section within the latter, and means operatively connected to one of the parts of the radio receiving set for adjusting the latter part including a revolute control element positioned above the top wall of the top section and removable as a unit with the latter wall.

4. In a combined article of furniture and radio receiving set, a stand having a hollow base section provided with a removable bottom wall, a hollow top section supported above the base section by a pedestal and having a removable top wall, a radio receiving set having a chassis unit housed in the top section and comprising a plu-

rality of parts of a radio receiving circuit, a loud speaker assembly supported in the top section and comprising a cone positioned directly beneath the chassis unit and facing the bottom of the latter, additional parts of the radio receiving circuit housed in the base section and removable with the bottom wall of the latter, tuning control elements supported above the top wall of the top section and operatively connected to certain parts of the radio receiving circuit through an opening in the top wall of the top section, means for securing the chassis unit, speaker assembly and tuning controls to the top wall of the top section for removal as a unit with the latter wall, and means accessible upon removing the bottom wall of the base section for securing the top wall of the top section in place.

5. In a combined article of furniture and radio receiving set, a stand provided with a base and a top section supported above the base, said top section having a top wall, a chassis unit comprising an assembly of a plurality of parts of a radio receiving apparatus suspended from the top wall, a loud speaker unit comprising a cone positioned directly beneath the chassis unit and facing the bottom of the latter, volume control means in the chassis unit having a vertical shaft extending through the top wall of the top section, tuning control means also located in the chassis unit and distributed around said shaft, a member mounted for rotation about the axis of said shaft and operatively connected to the tuning control means for actuating the latter, a vertically extending tubular shaft supported in concentric relation to the first named shaft and having the lower end connected to the revoluble member for rotating the latter, a pair of dial members supported one above the other for ro-

10 tation independently of one another about the axis of the first shaft and located above the top wall of the top section, means connecting one of the dial members to the tubular shaft, and means connecting the other of the dial members to the volume control shaft.

15 6. In a combined article of furniture and radio receiving set, a stand provided with a base and a top section supported above the base by a pedestal, said top section having a top wall, a chassis unit comprising an assembly of a plurality of parts of a radio receiving apparatus suspended from the top wall of the top section, a loud speaker unit suspended from the top wall of the top section and located between the chassis unit and upper end of the pedestal, volume control means centrally disposed in the chassis unit and having a vertical shaft extending through the top wall of the top section to a position above said wall, a plurality of variable condensers in the chassis unit spaced from each other around the axis of said shaft and each variable condenser having a rotor provided with a pinion, a revoluble driving gear mounted for rotation about the axis of said shaft and adapted to mesh with said pinions for simultaneously adjusting said condensers, a tubular shaft supported in concentric relation to the vertical shaft and having the lower end connected to the driving gear for rotating the latter, a pair of dial members supported one above the other for rotation independently of one another about the axis of the volume control shaft and located above the top wall of the top section, and means respectively operatively connecting the dial members to said shafts.

DANIEL J. CROWLEY.
